Luison Thompson
A. NEYS.

UNITED STATES PATENT OFFICE.

OLIVER EDWARD MERRELL, OF SYRACUSE, NEW YORK, ASSIGNEE TO MERRELL-SOULE COMPANY, OF SYRACUSE, NEW YORK, A CORPORATION OF NEW YORK.

CONCENTRATING PROCESS.

Application filed August 8, 1918. Serial No. 247,955.

To all whom it may concern:

Be it known that I, OLIVER E. MERRELL, a citizen of the United States of America, and resident of Syracuse, in the county of Onondaga in the State of New York, have invented new and useful Improvements in Concentrating Processes, of which the following, taken in connection with the accompanying drawings, is a full, clear, and exact description.

This invention relates to certain improvements in concentrating process and apparatus for carrying out the same.

The object of the invention is to produce an efficient process for producing concentrated or evaporated products of milk and similar substances which are subject to material injury by improper application of harmful temperatures.

In other words, the production of concentrated milk or similar products in which the natural properties of the solids have not been materially altered during the evaporating process.

Other objects and advantages relate to the specific features of the process, as will more fully appear from the following description taken in connection with the accompanying drawings, in which—

Figure 1 is an elevation partly in section, of an apparatus adapted for carrying out the process herein.

Figure 2 is a cross section on line 2—2, Figure 1.

The apparatus, as shown, comprises a ring-shaped casting —1— of substantially U-shape cross section having, in this illustration, a second ring-shaped casting —2— secured to the under side thereof, as by bolts —3—.

The casting —2— carries a jacket —3—, preferably of cylindrical form and having its lower end closed by plate —4—. Within the jacket —3— an annular container —4— is suspended from the casting —1—.

The container may, as illustrated, be formed of vertical concentric walls —5— and —6— formed of sheet metal or similar material and an annular bottom wall —7— secured to the walls —5— and —6— to form an annular chamber closed at its bottom.

The inner wall or cylinder —5— may be closed at its upper end, as by the upwardly

tapered or conical top —8— having at its central portion a bearing —9— for the shaft —10—.

The upper arm of the U-shape casting —1— carries a cylindrical section —11— of sheet metal or other suitable material, within the upper end of which is secured a casting —12— formed for interlocking engagement with the cap —13— of a vapor condensing apparatus —14—.

The wall —6— of the annular container preferably extends some distance above the casting —1— so that a trough —15— is formed between the wall —6— and the section —11— for the reception of the concentrated liquid overflowing from the annular container.

The casting —12— carries a suitable baffle —17— having a central opening —18— to permit the passage of vapor as hereinafter described. The baffle may be secured to the casting in any suitable way to permit its removal, as by screws or otherwise.

Within the annular container is positioned a suitable rotary beater mounted upon and actuated by the shaft —10—. This beater comprises a casting —18— mounted on the shaft —10— and formed with a series of, in this instance twelve, radiating arms, each arm carrying a vertically disposed paddle or blade —19— of substantially the same width as the radial width of the annular container and extending from the bottom thereof to a point preferably slightly above the cylindrical wall —6—.

The lower ends of these blades or paddles are preferably connected together at their inner and outer edges by concentric rings —20— and —21—, respectively, to add rigidity to the structure.

The upper ends of the blades or paddles —19— carry a ring-shaped plate —23— which may be secured thereto in any suitable manner, and upon this plate are mounted a series of supports —24— for a hood —25—, said hood spaced vertically a short distance from the upper surface of the plate —23— and provided with an inwardly tapered portion —26— terminating in a vertical flange —27— rotating within the opening in the baffle —17—.

The shaft —10— may carry a second baffle —28— arranged in alignment with the open-

ing in the plate —23— to prevent the direct passage of vapor through the opening in said plate to the vapor condensing apparatus.

5 The shaft —10— may, as shown, be removably keyed to a socket —29— containing a spring —30— for resiliently holding the shaft in contact with bearing —9—.

This socket —29— may carry an oil or 10 grease cup —30— adapted to collect oil or other foreign matter that may flow from the packed joint —31— for shaft —32—, of which the socket —29— forms an integral part.

15 Upon the shaft —32— is mounted a suitable beveled gear —33— for cooperation with a second beveled gear —34— carried by framework —35— and driven through any suitable connections, as by pulley —36—.

20 This construction may be of ordinary and well-known form.

The vapor condensing apparatus —14— embodies the usual condensing chamber —37— containing spray pipe —38— and 25 outlet —39— for water, the outlet being connected to any suitable device permitting maintenance of vacuum in the vapor condensing chamber.

The cap —13—, as shown, may be provided with an inwardly projecting flange —40— inclined upwardly to form a trough discharging into the vapor condensing apparatus for the reception of oil or other foreign matter that may be thrown from the 35 cup —30—.

The evaporating chamber and the vapor condensing chamber including the cap —13— are relatively movable toward and from each other to permit access to the interior of the apparatus and withdrawal of the beater when the baffle —17— is removed.

Steam or other heating fluid may be admitted to the chamber formed by the jacket —3— and the walls of the annular concentrating chamber through any suitable opening not herein shown or described, and a suitable condensation outlet —41— may be provided and may, if desired, be trapped in any suitable manner.

50 The milk or other liquid may be continuously supplied to the annular concentrating chamber through pipe —42— and the annular body of liquid within the annular concentrating chamber is heated both externally 55 and internally, and is stirred or mechanically moved over the heating surfaces at a desired rate of speed to effect the most advantageous results, and the speed is preferably sufficiently high so as to depress the central portion of the body of liquid below the bearing —9—, while the edge portions thereof are elevated sufficiently to overflow into the trough —15— so that a continuous discharge of the concentrated liquid is effected 60 into said trough and from the trough into

the tank —43— which is connected by pipe —44— to the vapor condensing apparatus —14—, whereby the same degree of vacuum is produced in the tank as exists in the vapor condensing apparatus and the concentrating chamber, thereby permitting a free discharge of the concentrated liquid.

Continuous removal of the condensed liquid may be effected by means of suitable discharging apparatus.

75 Preferably the inner wall —5— of the concentrating chamber is provided with a partition —45— extending across said wall at the base of the conical upper portion to prevent heating of said conical portion, thereby insuring a complete covering of the heated surface with the liquid.

The separation of the vapor from the liquid is hastened by the stirring effected through the rotary beater and the vapor is 85 separated from the annular body of liquid at the upper end of the same and discharged through the separating apparatus into the vapor condensing apparatus where it is immediately condensed to produce high vacuum in the apparatus.

By the term "high vacuum" as used in the specification and claims hereof, I mean a vacuum of upwards of eighteen (18") inches of mercury, and preferably in actual practice I employ a vacuum of upwards of twenty-six (26") inches of mercury corresponding to a milk vaporizing temperature of approximately 130°.

Although I have described one particular process and series of steps as perhaps preferable in carrying out my invention and one specific apparatus as peculiarly adapted for the purpose described, I do not desire to limit myself to the details of either the process or apparatus as various changes and substitutions may be made without departing from the spirit of this invention as set forth in the appended claims.

110 What I claim is:

1. The process of concentrating a substance containing liquid consisting in shaping the liquid in an annular body, heating the interior and exterior of the annular body to a temperature sufficient to vaporize 115 liquid constituents of the substance treated at the maintained pressure, mechanically moving the treated substance in a rotary direction, continuously supplying the substance to one end of the annular body, continuously discharging the concentrated substance from the opposite end of said body, and subjecting the body of substance to high vacuum.

2. The process of concentrating a substance containing liquid consisting in shaping the liquid in an annular body, heating the interior and exterior of the annular body to a temperature sufficient to vaporize 120 liquid constituents of the substance treated 125 at the maintained pressure, mechanically moving the treated substance in a rotary direction, continuously supplying the substance to one end of the annular body, continuously discharging the concentrated substance from the opposite end of said body, and subjecting the body of substance to high vacuum.

at the maintained pressure, mechanically moving the treated substance in a rotary direction, continuously supplying the substance to one end of the annular body, continuously discharging the concentrated substance from the opposite end of said body, separating the vapor from the body of liquid at the discharge end of said body, and condensing the separated vapor to produce high vacuum in the space about the body of liquid.

3. The process of concentrating a substance containing liquid consisting in continuously introducing the liquid into one end of an annular container having concentric annular treating surfaces, heating the interior and exterior surfaces of the annular body of liquid confined between said annular treating surfaces to a temperature sufficient to vaporize liquid constituents of the substance treated at the pressure maintained in the container, mechanically moving the substance relatively to said treating surfaces, continuously discharging the concentrated substance from the container, separating the vapor from the liquid at the discharge end of the body of substance, and maintaining high vacuum in the container.

4. The process of concentrating a substance containing liquid consisting in continuously introducing the liquid into one end of an annular container having concentric annular treating surfaces, heating the interior and exterior surfaces of the annular body of liquid confined between said annular treating surfaces to a temperature sufficient to vaporize liquid constituents of the substance treated at the pressure maintained in the container, mechanically moving the substance relatively to said treating surfaces, continuously discharging the concentrated substance from the container, separating the vapor from the liquid at the discharge end of the body of liquid, and condensing the vapor to produce high vacuum in the container.

separated vapor to produce high vacuum in 45 the container.

5. The process of concentrating a substance containing liquids consisting in introducing the liquid into one end of a container having an annular portion formed with concentric annular treating surfaces, heating the exterior and interior surfaces of the body of liquid confined between said annular treating surfaces to a temperature sufficient to vaporize liquid constituents of 55 the substance treated at the pressure maintained in the container, mechanically moving the substance relatively to said treating surface, continuously discharging the concentrated substance from the container, separating the vapor from the liquid at the discharge end of the body of substance, and maintaining high vacuum in the container.

6. The process of concentrating a substance containing liquid consisting in introducing the liquid into one end of a vertically arranged container having an annular portion formed with concentric annular treating surfaces, heating the interior and exterior surfaces of the annular body of liquid 65 confined between said annular treating surfaces to a temperature sufficient to vaporize liquid constituents of the material treated at the pressure maintained in the container, mechanically moving the substance relatively to said treating surface and in a rotary direction within said container, separating the vapor from the liquid at the upper end of the body of liquid, and condensing the vapor to produce high vacuum in 70 the container.

In witness whereof I have hereunto set my hand this 31st day of July, 1918.

OLIVER EDWARD MERRELL.
